UNITED STATES PATENT OFFICE

FRANK K. EDWARDS, OF LOCKLAND, OHIO, ASSIGNOR TO THE NIVISON-WEISKOPF COMPANY, OF READING, OHIO, A CORPORATION OF OHIO

DESIGN FOR A BOTTLE

Application filed July 24, 1929. Serial No. 32,189. Term of patent 7 years.

To all whom it may concern:

Be it known that I, FRANK K. EDWARDS, a citizen of the United States, residing at Lockland, in the county of Hamilton and State of Ohio, have invented a new, original, and ornamental Design for a Bottle, of which the following is a specification, reference being had to the accompanying drawing, forming a part thereof.

I claim:

The ornamental design for a bottle as shown.

FRANK K. EDWARDS.
